UNITED STATES PATENT OFFICE.

JOHN M. STRMIC, OF CHICAGO, ILLINOIS.

COMBINATION LOCK.

Application filed September 23, 1919. Serial No. 325,638.

To all whom it may concern:

Be it known that I, JOHN M. STRMIC, a citizen of the United States, residing at Chicago, in the county of Cook and State 5 of Illinois, have invented a certain new and useful Improvement in Combination Locks, of which the following is a full, clear, concise, and exact description, reference being had to the accompanying drawings, forming 10 a part of this specification.

The invention relates to locks and primarily to that type of these devices generally known as combination locks, the locking and unlocking of which is controlled by movable elements each of which 15 are moved a certain predetermined distance to effect an unlocking of the parts.

The invention has among its various objects the provision of an arrangement such 20 as above described which is simple, strong and durable in construction and which cannot be tampered with to effect a separation of the parts when the same are in locked relation.

It is a further object of the invention to 25 provide a device of this character with a means whereby the proper person may readily manipulate the mechanism so that he may without the aid of numerals etc. 30 determine when the controlling mechanism is positioned so as to permit a separation of the portions which are locked together.

It is an added object to provide a means 35 whereby the movement of one controlling element is prevented from being transmitted to another, thereby insuring that said elements will be retained in their proper position after being set to effect a separation or unlocking of the parts.

The invention has as a further object the 40 provision of means whereby the combination may be readily changed should this at any time be found desirable.

In the structure shown a plurality of 45 rotatable controlling elements are contemplated for controlling the locking and separation of the parts. The invention also has as an object the provision of a means whereby any strain which may be exerted 50 upon the parts to cause an unauthorized separation thereof when same are in locked relation, will be exerted upon the two elements which are locked together instead of upon the controlling elements.

It is another object of the arrangement 55 to provide means whereby the combinations

for controlling the separation of the lock may be varied by changing the relative positions of the parts.

The invention has these and other objects 60 all of which will be more readily understood when read in conjunction with the accompanying drawings, which will be explained in detail herein and in which

Fig. 1 is a longitudinal section of the construction showing the parts in locked relation;

Fig. 2 is a section similar to Fig. 1 showing the parts in position to permit a separation thereof;

Fig. 3 is a section taken on line 3—3 of Fig. 1;

Fig. 4 is a section taken on line 4—4 of Fig. 2;

Fig. 5 is an end view of one portion of 75 the device;

Fig. 6 is a section taken on line 6—6 of Fig. 2;

Fig. 7 is a longitudinal section similar to that illustrated in Figs. 1 and 2, showing 80 a modified construction which may be resorted to and which permits various combinations to be obtained;

Fig. 8 is a section taken on line 8—8 of Fig. 7, showing the parts in their relative 85 position to be controlled by one combination;

Fig. 9 shows the parts of Fig. 8 in a changed position which results in a different combination from that resulting from the 90 position of the parts as shown in Fig. 8;

Fig. 10 is a detail of a portion employed in the structure shown in Fig. 7; and

Fig. 11 is another modified arrangement which might be substituted for a similar 95 part in the devices shown in Figs. 2 and 7.

In the embodiment of the invention illustrated in the drawings the use of the two elements 10 and 11 to be locked together and unlocked from each other is contemplated. 100 These elements are each provided with an eyelet 12 whereby the opposite ends of a chain (not shown) may be secured thereto. The element 10 is further provided with the flanged portion 13 and the spindle or extension 14. This spindle has a reduced portion 15 arranged between the flange 13 and the end thereof. The element 11 also has an extension 16 which is provided with a central bore 17 for the reception of the 110 spindle 14. This spindle is held in locked relation with respect to the member 11 by

means of the mechanism generally designated 18, which when same is in the position illustrated in Fig. 1 engages both of said members 10 and 11, said mechanism being held in this position by the rotatable elements 19—20 and 21, which are rotatable upon the portion 16 of the part 11. These latter elements being rotatably held upon the portion 16 by the collar 22 between it and the flange 22^a. The member 22 is in turn held by the enlarged end 23 of the portion 16 and the screw 24 which is threaded into both the enlargement and the collar 22. This screw 24 is hidden from view by the flange 13 of the member 10, and consequently cannot be tampered with to permit of a separation of the parts when same are arranged in locked relation to each other.

From the foregoing it is evident that the rotatable elements 19, 20 and 21 are held in position upon the portion 16 and that the parts 10 and 11 may be disconnected without any danger of said rotatable elements becoming separated therefrom. The portion 16 is provided with a groove 25 and also carries the stationary discs 26, 27 and 28 which have the projections 29 (Fig. 6) which enter the groove 25 and thereby prevents any rotation thereof. These discs have a plurality of circumferentially arranged apertures 31—31, and a blank space 32. The apertures cooperate with the spring pressed detents 33 of each of the rotatable members 19, 20 and 21, and are provided to hold the rotatable elements in position and against accidental movement. These discs act as washers and prevent transmitting the movement of one of the rotatable elements to the other when rotated. As shown in Fig. 6 each of said discs is provided with a slot 34 which is arranged in alignment with the slot 35 provided in the portion 16 of the member 11. Each of the rotatable elements 19, 20 and 21 is also provided with a recess or cutaway portion 36, which when arranged in alignment with the slot 34 in the disc and the slot 35 in the portion 16, and with each other, permits the mechanism generally designated by the numeral 18 to release the spindle 14 which then allows this portion to be withdrawn from the bore 17. The mechanism 18 includes the bar 37, spring 38, and pin 39 which projects through the aperture 40 provided in the wall of the member 16, and into the reduced portion 15 of the spindle 14. When these parts are in the position shown in Fig. 1, it will be understood that the recesses 36 of the rotatable elements 19 to 21 are out of alignment with the slots 34 and 35, and thus the bar 37 is held against the action of the spring 38 by the concentric portion of the rotatable elements, which consequently causes the pin 39 to project

into the reduced portion 15 of the spindle 14, and prevents the withdrawal of this portion. It will further be understood that the bar 37 will be held in the depressed condition as long as any of the recesses 36 are not in alignment with the slots 34 and 35. Consequently all of the recesses must be in alignment, otherwise the bar cannot be moved by the spring 38 to release the spindle.

The operation of the device shown in Figs. 1 to 6 to unlock it is substantially as follows: The operator will rotate each of the rotatable elements 19, 20 and 21 in a clockwise direction, which will cause a clicking sound to be produced as the detents 33 enter the apertures 31 of the stationary discs 26 to 28. This sound will continue until the space 32 is reached, when it will be momentarily interrupted, warning the user to count the clicks. He knowing the particular number required to bring the slot 36 of each rotatable element into its proper position, will know when to stop operating each element. This will clearly be understood by referring to Fig. 3, as the fourth click after the space 32 indicates that the slot 36 is in alignment with the slot 35 of the portion 16. Thus when all of the slots 36 are in alignment with each other and with the slot 35 the bar 37 and projection 39 can be moved upwardly by the spring 38 which causes a disconnection of the portions 11 and 12, and permits of their separation. It is further evident that turning any one of the elements 19 to 21 immediately breaks the combination and if the spindle 14 at this time is inserted in the bore 17, the same will be held against separation from the member 11.

The enlargement or head 23 of the member 16 and the collar 22 have cooperating means for holding the collar with relation to the head before the screw 24 is inserted. This means permits of their separation after the screw 24 has been removed, and includes the inwardly projecting lugs 40—40 which are placed in alignment with the cutaway portions 41 and 42 of the head and passed over the same and turned a portion of a turn. This brings these lugs 40—40 out of alignment with the cutaway portions and in rear of the solid portion of the head which prevents its removal until the same is again turned to bring the lugs into alignment with the slots 41 and 42.

In Figs. 7 to 10 are illustrated an arrangement which may be resorted to and in which the combination necessary to permit of a release of the parts may be changed or varied. This structure corresponds in most of its elements with that shown in Figs. 1 and 2, differing only in the structure of the rotatable elements and the detent which operates therewith. In this structure the rotatable elements 43—43 are constructed of two separable parts 44 and 45, the element

45 having a series of circumferentially arranged slots 46—46 and the portion 44 having projections or ribs 47—47 which cooperate with their slots to hold the parts 44
5 and 45 in proper relative position, yet permit the same to be separated, the purpose of which will be explained in the following:

These portions 44 and 45 are each recessed as shown at 48 to accommodate the spherical 10 detent 49 of the stationary washer 50 shown in Fig. 10. The portions 44 and 45 are each provided with an unequal number of recesses 51 and 52 which when properly arranged with respect to each other produce 15 hemispherical recesses for the reception of the detent 49. By providing an unequal number of these recesses 51 and 52 a blank space as 53 is provided similar in purpose to the blank space 32 of the structure shown 20 in Figs. 1 to 6. The portion 44 is also provided with a slot 36^a similar in purpose to the slot 36 in Figs. 1 to 6, and the disc 50 is provided with a slot 34^a, the object of this being to permit the bar 54 to be elevated when the slots 36^a of the rotatable 25 elements of this latter structure are brought into alignment with each other and into alignment with the bar.

By constructing the rotatable elements of 30 this structure of two parts, 44 and 45, so that same may be shifted relatively to each other, the space 53 may be caused to assume a relatively different position with relation to the slot 36^a which consequently 35 changes the combination necessary to bring this slot into proper position to release the bar.

In the structure shown in Fig. 11 another arrangement for changing the combination is illustrated. When this structure is resorted to the extension corresponding to that designated 16 in Figs. 1 and 2 will be provided with a series of longitudinal slots 55. The disc 56 will be provided with the 45 projection 57 which may enter any of said slots. This disc will be further provided with a plurality of apertures 58—58 and slots 59—59, and blank space 60. This structure differs from those preceding in 50 that a plurality of slots 55 and 59 are provided in the disc and portion 16 and by shifting the disc circumferentially with respect to the portion 16 and by turning this disc so that the opposite disc face is presented to the detent, various combinations 55 can be obtained. For example, presume that the projection 57 is inserted in the uppermost slot to the right of Fig. 11. This will bring the blank space 60 of the disc to 60. position *a* and the slot *b* in alignment with the slot 35 in which the bar 37 is arranged. By shifting the disc so that the projection thereof is arranged in the uppermost left hand slot, the blank space 60 will be arranged at *c*. Now by reversing the disc so

that the opposite face is outermost with reference to Fig. 11, and by arranging the projection so that same is in the uppermost left hand slot of the member 16, the blank space 60 will be arranged at *d*. By shifting the disc so that the projection may enter the uppermost right hand slot the blank space will again assume a position at *c*. It being understood that placing the projection in any of the intermediate slots, various other 70 combinations will result. Thus by shifting this disc relatively to the slotted element the blank space will also be shifted closer to or further away relatively to the slot 61 within which the bar 37 is confined. This naturally necessitates various movements and results in various combinations.

The general operation necessary to permit of a separation of the parts is substantially as follows: Presuming that the combination 80 to unlock the parts shown in Figs. 1 and 2, is 4—3 and 2, the user will turn the rotatable element 19 in a clockwise direction until (Fig. 6) the successive clicking sound is momentarily interrupted. Thereafter upon 90 each recurrence he will count until the 4th click. This brings the slot 36 of this rotatable element into alignment with the slot 35, after which it is held in this position by its 95 detent 33. Movement of the elements 20 and 21 a number corresponding to that at which they are set brings the slots of these elements into alignment with a similar slot of a preceding rotatable element and into alignment with the slot 35 of the member 16. 100 This permits the bar 37 carrying the pin 39 to move upwardly and out of the reduced portion of the portion 10 which permits the members 10 and 11 to be separated. It 105 will be noted that any pulling strain which might be exerted upon the members 10 and 11 when same are in locked relation, is directed upon said members 10 and 11 and not upon the rotatable elements, also that the 110 rotation of any of said rotatable elements depresses the bar 37 and again locks the parts together.

From the foregoing explanation it is evident that a simple and effective arrangement is provided in which various combinations may be formed, also that the rotation of one part is not transmitted to another during rotation, and said parts are held in their adjusted position.

Having thus described the invention it is 120 obvious that changes and modifications may be resorted to without departing from the scope of the invention defined in the claims.

What I claim and desire to cover by Letters Patent is:

1. In a lock the combination of a pair of separable members, one of said members having an extension, said extension being provided with a bore, for the reception of the other member, a transverse aperture pro- 130

vided in said extension which communicates with said bore, a reciprocable member carried by said extension, a plurality of rotatable members also mounted upon the extension and having means for controlling the action of said reciprocable member, said reciprocable member having means which operates with the second mentioned member to releasably lock said separable members together, and means co-operating with the rotatable members for holding said members in adjusted position.

2. In a lock the combination of a pair of separable members, one of said members having an extension provided with a bore for the reception of the other member, a transverse aperture provided in said extension communicating with the bore, a reciprocable member carried by said extension, a plurality of rotatable members also mounted upon the extension and having means for controlling the action of the reciprocable member, said reciprocable member having an extension which operates in the transverse aperture, the other separable member having a portion constructed to be inserted into the bore of the first mentioned member, said last mentioned member having an annular portion provided to engage the extension of the reciprocable member to lock said separable members together.

3. In a lock the combination of a pair of separable members, one of said members having an extension which is provided with a bore, a transverse aperture provided in said extension which communicates with said bore, said extension being provided with a groove, a reciprocable member provided in said groove, said member having an extension which operates in the transverse aperture, a plurality of rotatable members arranged upon said extension, said members having means for controlling the actuation of said reciprocable member, the other separable member having a portion constructed to be inserted into the bore of the first mentioned member and having an annular portion co-operating with the extension provided upon the reciprocable member to lock said separable members together.

4. In a lock the combination of a pair of separable members, one of said members having an extension, said extension being provided with a bore for the reception of the other member, a transverse aperture provided in the extension which communicates with the said bore, a reciprocable member mounted upon the member having the bore, said reciprocable member having an extension which operates in said transverse opening to releasably engage said second mentioned member, a plurality of rotatable

members arranged upon the first mentioned member, said members being provided to control the action of the reciprocable member, means for holding said rotatable members in adjusted position, and means provided upon the first mentioned member for permitting the adjustment of said last mentioned means.

5. In a lock the combination of a pair of separable members, one of said members having an extension, a bore provided in the extension for the reception of the other member, a reciprocable member having means for releasably engaging said member which is inserted into the bore of the first mentioned member, a plurality of rotatable members arranged upon the first mentioned member, said rotatable members having means for controlling the action of the reciprocable member, a stationary member for each rotatable member for retaining said rotatable members in adjusted position, said last mentioned member being adjustable whereby the movement of the rotatable member may be varied to effect a release of the separable members.

6. In a lock the combination of a pair of separable members, constructed to be releasably connected together and rotatable with respect to each other when connected together, means for releasably connecting said members, rotatable means for controlling said first mentioned means, means co-operating with the first mentioned rotatable means for holding said first mentioned rotatable means in adjusted position, said second mentioned means having means for holding the same in its adjusted position.

7. In a lock the combination of a pair of separable members constructed to be releasably connected together, and rotatable with respect to each other when connected together, means for releasably connecting said members, rotatable means for controlling said first mentioned means and stationary means co-operating with the rotatable means for holding said rotatable means in adjusted position.

8. In a lock the combination of a pair of separable members constructed to be releasably connected together and rotatable with respect to each other when connected together, means for releasably connecting said members, rotatable means for controlling said first mentioned means, and adjustable means co-operating with the rotatable means for holding said rotatable means in adjusted position.

In witness whereof, I hereunto subscribe my name this 16th day of September A. D., 1919.

JOHN M. STRMIC.
